Atty.

UNITED STATES PATENT OFFICE.

MAX LEVINE, OF BROOKLYN, NEW YORK.

LOCK.

Application filed March 22, 1923. Serial No. 626,882.

To all whom it may concern:

Be it known that I, MAX LEVINE, a citizen of Russia, residing at Brooklyn, in the county of Kings and State of New York, 5 have invented certain new and useful Improvements in Locks, of which the following is a full, clear, and exact specification.

This invention relates to door locks, and has for its object to provide an improved 10 sliding bolt lock having a plurality of locking bolts adapted to move in unison and adapted to provide great resistance to attempts to force the lock.

Another object is to provide a sliding bolt 15 lock in which the bolt has three stages or positions of movement, one fully retracted, another projected to an intermediate stage in which said bolt may act as a spring lock or night latch, and another fully projected 20 stage in which said bolt can only be retracted by a positive actuation of a key or knob. A further object is to provide means for retaining the bolt in its fully retracted position in the casing, so that the door may be 25 freely opened without turning the key or knob. Other objects will appear as the description proceeds.

The invention will be first hereinafter described in connection with the accompanying 30 drawings, which constitute part of this specification, and then more specifically defined in the claims at the end of the description.

In the accompanying drawings, wherein 35 similar reference characters are used to designate corresponding parts throughout the several views:

Figure 1 is an elevation of a lock and keeper constructed substantially in accordance 40 with this invention, as they appear looking from the inside of a door to which they may be attached.

Figure 2 is a vertical section on the line II—II of Figure 1.

Figure 3 is a vertical section on the line III—III of Figure 2.

Figure 4 is a horizontal section on the line IV—IV of Figure 1.

Figures 5 and 6 are detailed side and plan 50 views, respectively, of one member of the tumbler of the lock.

Figure 7 is a vertical section on the line VII—VII of Figure 2.

Figure 8 is a section on the same line but 55 showing a different position of the bolt and part of the keeper broken away.

Figure 9 is another section on the same line showing the third position of the bolt.

Figure 10 is a section on the line X—X 60 of Figure 8.

Figure 11 is a section on the line XI—XI of Figure 12.

Figure 12 is a section on the line XII—XII of Figure 11, these two figures showing the bolt locked in its fully retracted position. 65

Figure 13 is a detailed view of the bolt with its three locking members.

Figures 14 and 15 are side and plan views, 70 respectively of the main pivoted member of the tumbler, and

Figure 16 is a plan view of the supplemental part of the tumbler, as shown in detail in Figures 5 and 6, assembled with the main tumbler member shown in Figures 14 and 15. 75

The bolt 1 illustrated in detail in Figure 13 is mounted to slide in a casing 2 being guided on posts 3 extending from the front wall 4 of said casing through slots 5 in the upper and lower portions of the inner or frame part of said bolt. Said bolt is also guided in the casing 2 by the three bolt members 6 working in slots 7 in the end wall 8 of said casing. The posts 3 have angular portions or blocks 3^a at their ends adjacent the front wall 4 of the casing for spacing the bolt frame 1 from said wall, as best shown in Figure 2. When the bolt members 6 are projected from the casing they are adapted to engage slots in a keeper 9 of suitable construction and which may be fastened to a door jamb by means of screws 10, the lock casing 2 being secured to the door 11, Figure 2, by screws 12 also shown in Figures 1 and 3 but omitted from the other views for the sake of clearness. 85

The bolt frame 1 is preferably made of thinner metal than the three parallel bolt members 6, there being a vertical wall or abutment 13 formed at the junction of said parts, against which a spring 14 presses for normally urging the bolt outward. Said spring 14 may be carried by a post 15 fast on the front wall of the lock casing. 90

The bolt frame 1 is also made with a horizontal slot 16 through which a lock spindle 17 extends, said spindle having a reduced end portion journaled in the knob 18 on the front wall of the casing 2, while the other end of said spindle has an angular 105 notch 19^a arranged axially thereof and engaged by a connecting bar 19 carried by

and actuated by a cylinder lock 20 secured by bolts 21 to the rear plate or wall 22 of the casing 2 and adapted to be arranged on the outer face of the door 11, as indicated in Figure 2, the spindle 17 being thus rotatable by the key 23 of the cylinder lock 20. Said rear plate 22 is secured to the posts 3 by screws 53. Said spindle 17 has a radially projecting roll back 24 for actuating the bolt as hereinafter explained. The knob 18, which is journaled in the front wall of the casing 2, also carries a roll back 25 which is adapted to actuate the bolt independently of the roll back 24 on the spindle 17, so that said bolt may be actuated either by the knob on the inside of the door or by the key to the cylinder lock on the outside of the door. Both roll backs are arranged in the plane of the bolt frame 1 and are adapted to engage in notches 26 and 27 in a horizontal bar 28 of said frame below the slot 16. Below said bar 28 there is another horizontal slot 29 in said bolt frame.

25 A tumbler 30 has its main member 31 arranged between the front wall of the casing 2 and the bolt frame 1, and pivoted at one end to a stud 31 on said front wall. Said main portion or member of the tumbler has a laterally extending lug 32 on its free end projecting through the slot 29 below the bar 28 of the bolt frame. A supplemental tumbler member 33 is arranged in rear of the bolt frame 1 and is secured to the main tumbler member by a screw 34 engaging said lug 32 and a superposed laterally projecting lug 35 on said supplemental member 33. The spacing of said members 31 and 33 is such as to permit the free sliding of the bolt frame between them.

The lug 32 on the main portion or member of the tumbler has an upstanding tooth or catch 36 adapted to engage in either of two notches 37 and 38 in the lower edge of the bar 28 of the bolt frame, said tumbler being urged upward to engage one of said notches by a spring 39 attached to a post 40 on the front wall of the casing 1 and bearing at its free end upon the under face of the lug 32. An abutment or lug 41 on said front wall of the casing is positioned to limit the upward movement of the free end of the tumbler to the proper level for the catch or tooth 36 to engage in one of the notches 37 and 38. When in this normal position, as shown in most of the figures of the drawing, the upper edges of the main and supplemental portions or members 31 and 33 of the tumbler are arranged slightly below the level of the upper edge of the bar 28 of the bolt frame, and said tumbler members overlap the notches 26 and 27, so that when either of the roll backs 24 or 25 is rotated about the axis of the spindle 17 by means of the key to the cylinder lock 20 or

the knob 18, respectively, the tumbler will be swung downwardly thereby for releasing the tooth or catch 36 from the one of the notches 37 or 38 engaged thereby, the roll back 24 engaging the supplemental member 33 of the tumbler, while the roll back 25 engages the main member 31 of said tumbler, as will be readily understood. The position of the tumbler when swung downward by one of the roll back preparatory to moving the lock frame by engaging with one of the notches 26 or 27 is indicated in dotted lines in Figure 11.

In Figures 3, 4, and 7, the bolt frame 1 is shown in its intermediate position with the three bolts 6 projected far enough to permit them to serve as a night latch or spring lock. It will be noted that the rear faces or corners of the free ends of said bolt members 6 are beveled off, as at 42, and that the notch 38 in the lower edge of the bar 28 of the bolt frame is wide enough to permit said spring action of the lock bolt. Thus, when the bolts are arranged in this intermediate position and the door carrying the lock is closed, the beveled ends 42 of said bolt members 6 will ride on the edge of the keeper and automatically retract said bolt against the action of the spring 14 until said members 6 register with the slots in the keeper 9, whereupon said spring advances the bolt to engage said slots in the keeper and thereby lock the door automatically. A coiled spring 43 is preferably arranged between the post 40 and a lug 44 on the lower edge portion of the bolt frame 1 for counterbalancing the action of said bolt frame under the tension of the spring 14 which is more powerful than said spring 43.

The bolt frame may be advanced from the position illustrated in Figure 7 to that shown in Figure 9 by revolving either of the roll backs, as already explained, said roll backs engaging the notch 26 in the bar 28 to effect this movement and also engaging the tumbler to release the catch 36 from the notch 38 and seat it in the notch 37 which is just wide enough to admit said catch and consequently holds the bolt frame against reciprocation when the bolt members are in their fully advanced position, Figure 9. It will thus be seen that when the bolt is in its fully advanced position it cannot act as a spring lock, but must be retracted by the key or knob.

The bolt frame may be moved from the position shown in Figure 7 to that shown in Figures 8 and 11 by revolving either of the roll backs in the opposite direction from that in which they are turned for fully advancing said bolt frame. In effecting this retracting movement of the bolt the roll back engages the notch 27 in the bar 28. The bolt may be fastened in this fully re-

tracted position by a vertically movable latch 45 consisting of a lug on a plate 46 having a handle or knob 47 extending through a slot 48 in the front wall of the casing 2 for actuating said latch. The plate 46 may be further guided by a stud 49 on the front wall of the casing engaging in a slot 50 in said plate, as best shown in Figure 9. Said plate may also have a depending portion 10 51 to cover the slot 48 in the front wall of the casing in which the knob 47 works. When the bolt is fully retracted, the latch plate 46 may be moved downward, as shown in Figures 11 and 12, to bring the latch proper or lug 45 into the path of a stud or projection 52 on the bolt frame 1, thus retaining the latter in its fully retracted position until said latch is raised to the position illustrated in Figures 9 and 10. In 15 20 this way the bolt may be fastened wholly within the casing 2 so that the door may be freely opened from the outside as well as from the inside without using a key or turning the knob 18.

25 I claim:—

1. The combination with a bolt casing having fixed guide posts therein, of a bolt having slots for guiding the same on said posts, and blocks on said posts for spacing 30 said bolt from the casing.
2. The combination with a bolt casing, of a reciprocatory bolt therein, a pair of roll backs co-axially arranged with respect to each other and both arranged in the plane 25 of the bolt, said roll backs being independently and permanently journaled in opposite walls of the casing and operable from opposite sides thereof, a pivoted tumbler having portions arranged on opposite sides

of said bolt, said bolt having notches to 40 be engaged by said roll backs and by said tumbler, respectively, and said tumbler having its portions at opposite sides of the bolt overlapping the notch to be engaged by the roll backs, whereby said roll backs will move the tumbler out of its notch prior to moving the bolt, one of said roll backs engaging the portion of the tumbler at one side of the bolt, while the other roll back engages the portion of the tumbler on the 45 other side of the bolt.

3. The combination with a bolt casing, of a reciprocatory bolt therein, a pair of roll backs co-axially mounted in the casing and extending into the plane of the bolt from opposite sides thereof, a tumbler comprising a main pivoted portion arranged at one side of the bolt and having a lateral lug provided with a locking tooth, and a supplemental tumbler portion arranged at the other side of the bolt and secured to said lug on the main portion, whereby both portions will move in unison, said bolt having notches to be engaged by said roll backs and by the tooth on the tumbler, respectively, 55 said portions of the tumbler normally overlapping the notch in the bolt to be engaged by the roll backs, whereby said roll backs are adapted to disengage said tooth from its notch prior to moving the bolt, one of 60 said roll backs engaging the main portion of the tumbler, and the other roll back engaging the supplemental portion of said tumbler.

In testimony whereof I have signed my name to this specification.

MAX LEVINE.
